DESIGN FOR AN INTEGRAL FLUSH TANK AND CLOSET BOWL

Frank G. Brotz and Gordon P. Gavin, Kohler,
Wis.

Application April 10, 1933, Serial No. 47,752

Term of patent 14 years

To all whom it may concern:

Be it known that we FRANK G. BROTZ and GORDON P. GAVIN, citizens of the United States residing at Kohler, in the county of Sheboygan and State of Wisconsin, have invented a new, original, and ornamental Design for Integral Flush Tanks and Closet Bowls, of which the following is a specification, reference being had to the accompanying drawing, forming part thereof. Figure 1 is a side elevation of an integral flush tank and closet bowl; Fig. 2, a front elevation thereof; Fig. 3, a plan view thereof; and Fig. 4,

a perspective view thereof, on an enlarged scale, showing our new design. The dominant feature of the design is the configuration of the top of the bowl which extends from a rounded front portion thereof, on lines substantially tangential to said rounded front portion, to points near the outer extremities of the tank.

We claim:

The ornamental design for an integral flush tank and closet bowl as shown and described.

FRANK G. BROTZ.
GORDON P. GAVIN.
